ALTERNATOR MECHANISM

Kenneth C. Zeh, Chicago, Ill., assignor to Raymond T. Moloney, Chicago, Ill.

Application May 3, 1939, Serial No. 271,568

4 Claims. (CL 175—335)

The invention relates to an alternator mechanism.

In certain apparatus such as in some types of games for amusement, there are two check or reward dispensing receptacles. It is desirable that for every predetermined number, say one thousand plays of the game, that a reward check be automatically deposited from a storage magazine into one of the dispensing receptacles. Also, it is desirable thereafter when another number of plays such as another thousand, have been made, that a check be dropped from the storage magazine into the other of the two receptacles. In such fashion, alternately, then, it is desirable to cause checks or the like to be fed into these receptacles to load same.

The primary object of the invention therefore is to provide an alternator mechanism, serving alternately to control means operative for any purpose such for example as to cause feeding of checks or the like to a pair of receptacles.

Another object is to provide an electromechanical alternator mechanism.

Still another object is to provide an electrical system embodying a pair of electromagnetic devices in separate circuits with respective control switches therein operable by a mechanical means to determine the time of closing of the switches and consequent operation of the electromagnetic devices.

Still another object is to provide a novel switch control member for use in the alternator mechanism.

Other important objects will become apparent to those skilled in this art as the disclosure is more fully made.

Briefly, these desirable objects may be achieved in one practicable form in the provision of a unit including a support carrying a ratchet wheel operating reduction gears, the last gear of which carries a pin, which in a certain point in its turning movement engages and closes a normally open blade contact switch disposed in an electric circuit. The ratchet wheel which is stepped up by any suitable mechanical means, also carries a pin operable in a certain angular position to close another normally open blade contact switch in the circuit. When these two switches are closed at the same time a circuit is completed through a double contact alternator blade switch to cause energization of an electromagnetic device, which thereupon operates for the desired purpose. The final gear has its pin positioned in a certain angular position of the said gear to turn through ninety degrees, a novel form of control member

being provided which includes means to govern opening and closing of said alternator switch. In one position of the latter one electromagnetic device is energized and in another position the other electromagnetic device is energized. In the present disclosure the movable parts of the unit are so proportioned and timed that for one thousand steps of rotation of the ratchet wheel one electromagnetic device is energized and when two thousand steps of the ratchet wheel are made the other electromagnetic device is energized. Thus on every thousand step ups of the ratchet wheel one or the other of the electromagnets is energized in alternation.

In the sheet of drawing illustrating a practicable embodiment of the invention:

Figure 1 is a general plan view of the improved alternator mechanism, including a typical wiring diagram; and,

Figure 2 is a front elevational, or end view of the structure shown in Figure 1.

The structure includes a support 10 in the form of a plate which carries a shaft 11 journaling for rotation, a ratchet wheel 12, said wheel having the desired number of usual teeth on its periphery and carrying on a face a perpendicular pin 23 near the peripheral edge of the wheel, as shown. The support pivotally carries a dog 14 urged by a spring 15 into engagement with the teeth of the ratchet wheel to prevent retrograde movement of the latter. Pivotally connected about the axis of the shaft 11 is a lever 16 pivotally carrying a spring pressed pawl 17 positioned to engage the teeth of the ratchet wheel. A pull spring 18 connected between the support and lever arm 16 normally holds the latter back to the position shown in Figure 1 with the pawl 17 in disengaged position with respect to the ratchet wheel, as will be obvious. A movable member 20 is indicated as the means to abut and move the lever arm 16 to cause step ups of the ratchet wheel. This member 20 in practice could be the usual coin released slide usable in a game to coin release the same for play, said member 20 being carried in a game cabinet for manual sliding movement in a push-pull manner.

The support 10 carries an insulated block 21 for mounting a spring blade contact switch 22 one blade of which is bent as at 13 to be in a position where it can be engaged by the pin 23 on the ratchet wheel 12. In this manner the switch 22, which is normally open, can be held closed once for each revolution of the wheel 12. The support 10 carries another insulated block 24 for mounting a second spring blade contact switch 25, there

being associated with this normally open switch, an insulated abutment blade which, as will later appear, acts to close the said switch 25.

- At another location on the support 10 is carried 5 still another insulated block 27 which serves to carry two spring blade contact switches 28 and 29 having a common center blade 30, which has an extended bent end 31 curved in an arc for a purpose later to appear.
- 10 These switches described are disposed in an electric circuit including a main plus lead 32 from the source of electrical energy to one side of the switch 25. From the other side of said switch, a wire 33 connects to one side of the switch 22 and from the opposite side of the latter switch, a wire 34 leads to the center blade 30 of the double switch 28, 29. From the other side of the switch 28 a wire 35 leads to one side of an electromagnetic device 36 which may be a magnet, a solenoid, or a 15 motor. From the device 36 a wire 37 has connection with a minus wire 38 going back to the source of energy. From the other side of the switch 29, a wire 39 leads to a second electromagnetic device 40 similar to the one 36, described, and from the other side of said device 40 is the wire 37 which has connection with the main lead 20 38.

It will be understood the shaft 11 carries a spur gear for rotation with the ratchet wheel 12 and 25 said gear meshes with and drives a gear 41, as shown. Said gear 41 meshes with and drives a set of speed reduction gearing 42, the final gear of this set being shown at 43 and relatively large and slow moving and carrying on one face near its 30 periphery a perpendicularly disposed pin 44. The plate or support 10 adjacent said gear 43 carries a shaft 45 on which is turnably carried a cross shaped alternator control member 46. Each leg of this member has a substantially radial edge 47 35 and an angularly disposed opposite radial edge 48 which merges with an outer curved cam edge 49 with the other edge 47 to form a cam edge head portion.

Two of the arms, diametrically opposed, are 40 of the same length and relatively short, whereas the other two arms, also diametrically opposed, are elongated by means of a round headed extension portion 50. These four legs are angularly spaced apart ninety degrees. All four legs 45 are engageable by the pin 44 on wheel 43, but only the long legs 50 can engage the part 31 of switch blade 30. This completes the detailed 50 description of the parts.

In operation the member 20 in a push-pull 55 manner is operated to swing the lever arm 16, thereby moving the ratchet wheel 12 one step by the pawl 17. As viewed in Figure 1 the wheel 12 turns clockwise and through the gearing 42 causes wheel 43 to turn counterclockwise. The 60 parts are so proportioned that when the wheel 12 has turned one thousand steps a conjunctive closing of switches 22 and 25 by respective pins 23 and 44 occurs. At this time the cross member 46 has one arm 50 positioned to flex part 31 and hold switch 28 closed whereupon current flows 65 through the described circuits to cause energization of the device 36 to operate a suitable auxiliary such as a check or coin ejector, not shown. By the time the wheel 12 has made another one thousand 70 steps the pin 44 will have moved to ride along the curved head 49 of the arm extending over the wheel 43 and cause turning of the cross member 46 to clear the long arm 50 from the part 31 so that switch 29 closes and switch 28 opens, where- 75 upon device 40 is energized for the purposes

stated. The cross member 46 is turned clockwise and the sides of its arms are specially formed as tracks along which the pin 44 rides in an obvious manner to cause proper turning of the member 46 so that each of the arms thereof at the proper instant will have a position controlling the switches 28 and 29. The alternator mechanism thus works to cause energization of the device 36 every two thousand steps of the wheel 12 and the device 40 also every two thousand steps, but they 10 alternate so that for every one thousand steps one of the devices 36 or 40 is operative.

It can thus be seen that a simple and useful structure for the purposes stated has been provided. 15

It is the intention to cover herein all changes and modifications of the example shown for purposes of the disclosure, which do not in material respects constitute departures from the spirit and scope of the invention as hereinafter claimed. 20

What is claimed is:

1. In an alternator mechanism, a support, a ratchet wheel journaled thereon, means to operate said wheel step by step, reduction gearing operable by said wheel, an abutment on a face of the wheel, an abutment on a face of the final gear of the gearing, two independent normally open switches disposed in a circuit and respectively disposed adjacent the wheel and final gear to be closed by the abutments thereon at certain angular positions of the wheel and gear, a pair of blade switches having respective circuit connections with electromagnetic devices, and a control member operable by the gear abutment for alternately closing the pair of switches and causing alternate operation of the electromagnetic devices. 35

2. In an alternator mechanism, a support, a ratchet wheel journaled thereon, means to operate said wheel step by step, reduction gearing operable by said wheel, an abutment on a face of the wheel, an abutment on a face of the final gear of the gearing, two independent normally open switches disposed in a circuit and respectively disposed adjacent the wheel and final gear to be closed by the abutments thereon at certain angular positions of the wheel and gear, a pair of blade switches having respective circuit connections with electromagnetic devices, and a control member operable by the gear abutment for alternately closing the pair of switches and causing alternate operation of the electromagnetic devices, said control member being turnably carried on the support in a position to be engaged by the gear abutment and to engage a blade of the pair of blade switches. 50

3. In an alternator mechanism, a support, a ratchet wheel journaled thereon, means to operate said wheel step by step, reduction gearing operable by said wheel, an abutment on a face of the wheel, an abutment on a face of the final gear of the gearing, two independent normally open switches disposed in a circuit and respectively disposed adjacent the wheel and final gear to be closed by the abutments thereon at certain angular positions of the wheel and gear, a pair of blade switches having respective circuit connections with electromagnetic devices, and a control member operable by the gear abutment for alternately closing the pair of switches and causing alternate operation of the electromagnetic devices, said control member being turnably carried on the support in a position to be engaged by the gear abutment and to engage a blade of 65 70 75 80 85 90 95

the pair of blade switches, all of the said turning parts being on axes parallel to each other.

4. For a circuit including a pair of switches and a pair of electromagnetic devices, means to cause alternate operation of the devices comprising an alternator mechanism including a double switch, mechanical means including a ratchet wheel and gearing driven therefrom to cause alternate clos-

ing of the double switch and at certain angular positions of the wheel and gearing simultaneous closing of the first switches whereby for every predetermined number of step ups of the ratchet wheel one device is energized and for the next 5 same predetermined number of step ups of the wheel the other device is energized.

KENNETH C. ZEH.
